UNITED STATES PATENT OFFICE

STAFFORD TROTTMAN, OF MILWAUKEE, WISCONSIN

TIMEPIECE

Application filed August 9, 1929. Serial No. 384,550.

This invention pertains to time pieces, such as watches, clocks, and the like, and has primarily for its object to provide a structure whereby the exact time may be more readily determined than in conventional time pieces provided with hour and minute hands, and without mental computation or effort.

A further object is to eliminate the conventional crystal, which requires frequent replacement as a result of breakage.

Incidental to the foregoing, a more specific object resides in the elimination of the hour and minute hands and the substitution of a single driven dial upon which the hours and minutes are indicated, the correct time being visible through a magnifying lens carried by the case.

A further object is to simplify the structure of time pieces by the elimination of gearing and extra shafts required to drive the usual hands.

With the above and other objects in view, which will appear as the description proceeds, the invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings is illustrated one complete example of the physical embodiment of the present invention constructed according to the best mode so far devised for the practical application of the principles thereof.

In the drawings, Figure 1 is an elevational view of a watch constructed in accordance with the present invention, parts being broken away to more clearly illustrate the structural features;

Figure 2 is a similar view of a modified form of the invention;

Figure 3 is a detailed transverse section taken on the line 3—3 of Figure 2.

While the invention has been illustrated and will be described as applied to a watch, it is to be understood that the same refers

in general to any type of time piece. Therefore, the language of the specification is to be so interpreted.

Referring now more particularly to the accompanying drawings, the numeral 1 designates a case provided with a cover 2. Contained within the case is the usual clock mechanism, only a portion of which is shown, as this forms no particular part of the present invention, which contemplates the use of any conventional mechanism well-known to those skilled in the art.

As stated in the foregoing objects, the present invention eliminates the use of indicating hands and substitutes a dial 3, which is mounted upon the usual hour hand shaft 4, driven by the gear 5. An arm 6, carried by the case in any suitable manner, extends over the dial and serves as a bearing for one end of the shaft 4, the other end being journaled in the usual manner. While the dial 3, in the structure illustrated, is secured to the shaft 4, it is obvious that the same may be fastened directly to the gear 5.

Contained on the dial 3, adjacent its periphery, are indicia 7 indicating the hours and minutes in a day. Obviously, in order to include all of the hours and minutes, the indicia must necessarily be very small in size. Therefore, in order to render the same visible, the cover 2, which is provided with a rectangular opening 8, in register with the indicia 7, is provided with a magnifying lens 9 which serves to magnify the numerals so that they may be readily seen.

From the foregoing description, taken in connection with the drawings, it will be seen that a very simple structure has been provided which eliminates use of hour and minute hands, and which enables the exact time of day to be readily ascertained at a glance without effort or computation upon the part of the user. Obviously, inasmuch as the dial 3 is carried by the hour shaft, the same will rotate once in twelve hours, and the indicia contained thereon will include twelve hours and the intermediate minutes.

It will be appreciated that the present structure eliminates the necessity of a cry-

tal and resulting breakage, thus affording a simple and durable structure.

In the simplified form of the present invention, it is not contemplated to indicate the "seconds". However, in instances where it should be desired to show the seconds, I propose to accomplish the same by the modified structure illustrated in Figure 2, in which the dial 3 is formed of any suitable transparent material having its outer edge provided with a frosted or colored band portion 10 adapted to receive the indicia 7. This leaves the central portion 11 of the dial transparent in order that a "second" dial 12, positioned under the dial 3, may be visible. Obviously, in this instance, the cover 2 must be provided with an opening 13 to render the dial 12 visible. The opening 13 may be provided with the usual crystal 14. However, due to the extremely small size of the opening 13 and the crystal 14, the latter is not as subject to breakage as the usual large crystal covering the entire face of the watch. Obviously, the dial 12 may be mounted upon the shaft 15, which drives the usual "second" hand, and in operation, as the dial is rotated, the "seconds", indicated on the dial, are determined by means of a hair line or other indicating point 16, contained on the crystal 14. Thus, a simplified structure may be provided which will readily give the "seconds", as well as the hours and minutes.

I claim:

1. A time-piece comprising a case having a cover provided with an opening, a clock mechanism contained within said case, a dial driven by said clock mechanism, indicia contained on said dial indicating the hours and minutes of the day, and a magnifying lens for said opening to render one of the indicia visible at a time.

2. A time-piece comprising a case having a cover provided with a pair of openings, a clock mechanism contained within said case, a transparent dial driven by said clock mechanism, indicia contained on said dial adjacent its periphery for indicating the hours and minutes of the day, said indicia adapted to register with one of said openings, and a "second" dial driven by said clock mechanism and positioned below said transparent dial and visible through the other of said openings in said cover.

In testimony that I claim the foregoing I have hereunto set my hand at Milwaukee, in the county of Milwaukee and State of Wisconsin.

STAFFORD TROTTMAN.
